UNITED STATES PATENT OFFICE.

WILLIAM J. KRIETER AND EDWARD L. FETH, OF CHICAGO, ILLINOIS, ASSIGNEES TO
DUFFY A. MATOT, OF CHICAGO, ILLINOIS.

REFRIGERATOR.

1,404,302.

Specification of Letters Patent. Patented Jan. 24, 1922.

Application filed September 28, 1921. Serial No. 503,902.

To all whom it may concern:

Be it known that we, WILLIAM J. KRIETER and EDWARD L. FETH, citizens of the United States of America, and residents of Chicago, county of Cook, and State of Illinois, have invented a new and useful Improvement in Refrigerators, of which the following is a specification.

This invention relates to refrigerators designed to receive ice-cream bricks in a plurality of columns according to flavors and is intended for use in stores where such ice-cream bricks are retailed. An object of the invention is to provide a refrigerator of this class wherein a receptacle for ice-cream bricks inside of the container may be surrounded by ice at its sides and top but having provision for the convenient removal of bricks from the bottom of each tier of bricks. A further object of the invention is to provide an improved drain for the ice-containing compartments which drain is in the form of a coil below the brick-containing compartment and serves, by the brine passing therethrough, to refrigerate the lower end of the brick-containing compartment.

The objects of the invention are accomplished by the design shown in the accompanying drawings wherein,

Figure 1 is a view in front elevation showing a refrigerator constructed in accordance with this invention.

Figure 2 is a sectional view taken on a line 2—2 of Figure 1.

Figure 3 is a sectional view taken on a line 3—3 of Figure 2.

Figures 4 and 5 are respectively plan sections taken on lines 4—4 and 5—5 of Figure 2.

The objection to refrigerators as at present designed for the retailing of brick ice-cream is the liability of the wrappings of the individual bricks coming in contact with salt water and the difficulty of removing ice from the top of the container and selecting the desired brick and the loss in the cooling effect of the ice by opening the refrigerator either at the top or throughout a large space at the front.

With the present construction bricks of a

selected flavor may be rapidly removed from the refrigerator without exposing the ice therein to the outer atmosphere and without requiring the lifting or removal of 55 bricks above the selected brick. The construction as illustrated in the drawings comprises a refrigerator having the generally approved arrangement of insulated walls and removable top through which the bricks 60 and ice are passed in filling the refrigerator. The brick container proper consists of a centrally located receptacle having an individual cover and partitioned to provide individual compartments for bricks of different flavor. At its lower end the rear wall of this brick container is inclined forwardly so that the lowermost bricks of each column will be projected forwardly slightly, 65 due to the weight of the bricks above them, 70 into position for convenient removal through a door at the lower end of the refrigerator. A coil of pipe is located at the lower end of the brick container and serves as a drain and cooling medium, this coil being in communication with the ice-containing compartment at its lower end to receive brine therefrom.

Referring to the drawings, the exterior casing 1 is in the form of double walls 2 80 and 3 between which is placed insulating material 4. The casing is provided with a removable cover or closure 5 and at its lower front end with a hinged door 6. This door communicates with the lower end of a brick 85 containing compartment 7. This compartment is centrally located within the surrounding casing which is preferably formed of sheet metal walls 8. The brick containing compartment is provided with a removable 90 cover 9 and its rear wall as indicated in Figure 2 is inclined downwardly and forwardly at its lower end 10 in order that the lowermost bricks will be projected forwardly a slight distance by the weight of 95 the downwardly moving column of bricks when one is removed from the lower end. The bottom 11 of the brick container is spaced upwardly from the floor 12 of the refrigerator casing in order that the forwardly projected bricks may be removed 100 and to provide a space for a refrigerating

coil 13 in the compartment 7. This coil at its end 14 communicates with the lower end of the ice containing compartment 15 and at its opposite end 16 leads out of the refrigerator so that the coil may serve as a drain. A separate drain 17 is provided in order that the apparatus may be more rapidly and thoroughly drained when washed.

10 The brick container 7 is provided with a plurality of longitudinally extending partitions 8 in order to divide this container into individual compartments for bricks of different flavor and in the operation of the 15 device these separate compartments are filled accordingly. The cover 9 is then placed upon the brick container and ice is packed around all of the side walls of this container and over the cover. Then the refrigerator cover 5 is replaced and it is not necessary to remove either of the covers 5 or 9 until the supply of bricks and ice is replaced. The lowermost brick of each column of bricks is projected forwardly as indicated in Figure 2 and therefore may be easily removed. Since the door 6 does not allow the outer air to enter the ice containing compartment there is comparatively little loss due to the opening of this door 25 and such loss is substantially compensated for by utilizing the drain 13 of the ice containing compartment as a refrigerating coil within the brick containing compartment 7.

Although but one specific embodiment of 30 this invention has been herein shown and described, it will be understood that numerous details of the construction shown may be altered or omitted without departing

from the spirit of this invention as defined by the following claims.

We claim:

1. A refrigerator of the class described having surrounding walls and an article receiving receptacle, the walls of which are spaced inwardly from the refrigerator walls thus providing an ice receiving compartment between the refrigerator walls and the article receptacle, said receptacle having one of its walls inclined inwardly at its lower end, a refrigerator door communicating with said article receptacle opposite the inclined portion of its wall, and a drain for the ice containing compartment in the form of a coil located in the article-containing compartment.

2. A refrigerator of the class described having surrounding walls and an article receiving receptacle, the walls of which are spaced inwardly from the refrigerator walls thus providing an ice receiving compartment between the refrigerator walls and the article receptacle, said receptacle having one of its walls inclined inwardly at its lower end, a refrigerator door communicating with said article receptacle opposite the inclined portion of its walls, vertically extending apparatus dividing said article containing receptacle into a plurality of compartments, and a drain for the ice containing compartment in the form of a coil located in the article-containing compartment.

Signed at Chicago this twenty-sixth day of September, 1921.

WILLIAM J. KRIETER,
EDWARD L. FETH.
